(57) **CLAIM**

The ornamental design for a fruit and vegetable nanometer purifier, as shown and described.

DESCRIPTION

FIG. 1 is a front view of a fruit and vegetable nanometer purifier, showing my new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof; and,

FIG. 8 is a second perspective view thereof.

The broken lines present in the figures are included for the purpose of illustrating portions of the fruit and vegetable nanometer purifier which form no part of the claimed design.
